UNITED STATES PATENT OFFICE.

AUGUSTUS BROWN MORISON, OF JERSEY CITY, NEW JERSEY, ASSIGNOR TO
THE CO-OPERATIVE BUILDING PLAN ASSOCIATION, OF NEW YORK, N. Y.

DESIGN FOR THE EXTERIOR OF A HOUSE.

SPECIFICATION forming part of Design No. 20,091, dated August 12, 1890.

Application filed July 15, 1890. Serial No. 358,843. Term of patent 7 years.

To all whom it may concern:

Be it known that I, AUGUSTUS BROWN MORISON, of Jersey City, in the county of Hudson and State of New Jersey, have invented and produced a new and original Design for the Exterior of a House, of which the following is a specification, reference being had to the accompanying drawings, forming a part thereof.

10 Figure 1 represents a perspective view of a house showing my design. Fig. 2 represents a horizontal section or plan of the first story. Fig. 3 represents a horizontal section or plan of the second story.

15 Similar letters of reference designate corresponding parts in all the figures.

A house of this design consists of two stories with an attic third story contained partly within a hip and partly within a gable roof, 20 and has an extension in the front with a bay on each floor, a projecting portion to the first floor on one side, the roof of which forms a balcony at the second floor, and a second projecting portion on the opposite side from the 25 first and second stories, a veranda extending along a portion of the front and a portion of one side of the first story, and a second veranda at the rear extending about two-thirds of the width of the house, both verandas being covered by shed roofs, all as hereinafter

more particularly described in detail with reference to the drawings.

A B C designate the exterior of the first and second stories and attic, the portions represented at the front of the house being partly 35 comprised in an extension D, having a gable roof E projecting from the main hip roof F. The extension D has bays a a at the first and second stories. At the first story on one side of the house and extending for about one-half 40 the depth thereof projects a portion G, the roof of which forms the floor of a balcony g on the second floor, and on the opposite side at the first and second stories a portion H projects, which is surmounted by a gable roof h, 45 said projecting portion extending partially over a veranda I, with a shed roof i. At the front of the house, commencing at the angle formed by the extension D, is another veranda J, surmounted by a shed roof, said veranda 50 extending along the front and one side of the house as far as the beginning of the projecting portion G.

What I claim as my design is—

The design for the exterior of a house, substantially as herein shown and described.

AUGUSTUS BROWN MORISON.
